UNITED STATES PATENT OFFICE.

GEORGE HERBERT FENSON, OF TORONTO, CANADA.

DESIGN FOR A BADGE.

SPECIFICATION forming part of Design No. 29,013, dated July 12, 1898.

Application filed May 28, 1898. Serial No. 681,517. Term of patent 7 years.

To all whom it may concern:

Be it known that I, GEORGE HERBERT FENSON, a subject of Her Majesty the Queen of Great Britain, residing in the city of Toronto, 5 in the county of York, in the Province of Ontario, Canada, have invented and produced a new and original Design for a Badge, of which the following is a specification, reference being had to the accompanying drawing, forming part thereof.

The drawing is a face view of the badge.

The leading feature of my design consists of a heart divided down the center from the center of the broad V-shaped top to the bottom apex and having a representation of the 15 British ensign on one side and the American ensign on the opposite side.

A is one side of the heart, which has a British ensign containing the Union Jack *a*, and B is the opposite side, having the American 20 ensign, commonly known as the "Stars and Stripes."

C is a ribbon with bifurcated ends which affords space for any desired words.

What I claim is—

The design for a badge herein shown and described.

GEORGE HERBERT FENSON.
